DESIGN FOR A DIAPHRAGM INSERTER

Carl C. Waterbury, Chicago, Ill.

Application August 28, 1939, Serial No. 86,921

Term of patent 14 years

To all whom it may concern:

Be it known that I, Carl C. Waterbury, a citizen of the United States and a resident of Chicago, in the County of Cook and State of Illinois, have invented a new, original, and ornamental Design for a Diaphragm Inserter, of which the following is a specification, reference being had to the accompanying drawing, forming part thereof.

Figure 1 is a perspective view of a diaphragm inserter showing my new design;

Figure 2 is a side elevation thereof; and

Figure 3 is a plan view thereof.

I claim:

The ornamental design for a diaphragm inserter, substantially as shown.

CARL C. WATERBURY.
